(57) **CLAIM**

The ornamental design for a remote trainer unit, as shown and described.

DESCRIPTION

FIG. 1 is a front view of a remote trainer unit showing my new design;

FIG. 2 is a right sided view thereof;

FIG. 3 is a left sided view thereof;

FIG. 4 is a back view thereof; and

FIG. 5 is a top view thereof; and,

FIG. 6 is a bottom view thereof.

The broken lines shown in the drawings form no part of the claimed design.
